UNITED STATES PATENT OFFICE

2,510,665

DIAPER

Alexander H. Sonnenberg, New York, N.Y.

Application August 11, 1948, Serial No. 43,614

1 Claim. (Cl. 128—284)

2

This invention relates to diapers. It is a principal object of my invention to provide a diaper which is very easy to secure on an infant and can be adjusted readily to accommodate for growth or to fit infants of different sizes. It is a further object of my invention to provide an adjustable diaper of the character described which employs no metal fastening elements, such for instance as pins or snap fasteners, and does not use buttons or the like which are liable to be broken or lost in laundering.

More specifically, it is an object of my invention to provide a diaper of the character described which employs tapes for holding the diaper in place, the diaper being of such construction that by following certain simple instructions as to the use and placement of the tapes, the diaper can be adjusted quickly to accommodate infants of different sizes. It is an additional object of my invention to provide a diaper of the character described which in all its adjusted positions will furnish excellent abdominal support.

Other objects of my invention will in part be obvious and in part will hereinafter be pointed out.

My invention accordingly consists in the features of construction, arrangements of parts, and combinations of elements which will be exemplified in the construction hereinafter described and of which the scope of application will be indicated in the appended claim.

In the accompanying drawings in which is shown one of the various possible embodiments of my invention:

Fig. 1 is a perspective view of an infant wearing a diaper embodying my invention;

Fig. 2 is a perspective view of the diaper as it appears when arranged for use on a large infant;

Fig. 3 is an enlarged fragmentary sectional view taken substantially along the line 3—3 of Fig. 2;

Fig. 4 is a perspective view similar to Fig. 2, but illustrating the diaper arranged for use on a smaller infant;

Fig. 5 is an enlarged fragmentary view taken substantially along the line 5—5 of Fig. 4;

Fig. 6 is a fragmentary sectional view taken substantially along the line 6—6 of Fig. 5;

Fig. 7 is a view similar to Fig. 4, but showing the diaper arranged for use on a still smaller infant; and

Fig. 8 is a plan view of the diaper laid out flat.

Referring now in detail to the drawings, the reference numeral 10 denotes a diaper embodying my invention. Said diaper comprises a fab-

addition, portions of the tape intermediate its ends are secured to the panel, as by stitching 40, 42, 44. Thus, the single tape 32, in effect, forms the four loops 24, 26, 28 and 30. Any suitable spacing may be employed for the loops as later will be appreciated. However, I have found that good results are obtained where the center spacing between the loops is one and three-quarter inches.

Further, pursuant to my invention, the portion of the panel on the opposite side of the crotch zone, i. e. the back portion 22, is provided with two series of means which are so constructed that they are adapted to have the elongated flexible members threaded therethrough. Desirably, these means, like the means heretofore described, are in the form of loops, and like the aforesaid means, each set of loops can be formed by a single tape. These two series of means are disposed on opposite sides of the longitudinal axis of symmetry of the diaper, preferably being located near the lateral edges of said diaper at the back portion. Said two series of means likewise are substantially linearly arranged in a direction parallel to the longitudinal axis of the panel.

As shown herein, each of said two series of means comprises a tape 46 or 48, one tape being disposed adjacent one lateral edge of the rear portion of the diaper, and the other tape being disposed adjacent the other lateral edge of said portion of the diaper. One end of each tape is adjacent the rear edge 50 of the panel, and the opposite edge, near the crotch section. The two ends of each tape, as well as three equally spaced intermediate portions, are held to the panel by stitching, whereby the tape 48 is, in effect, subdivided into four loops 52, 54, 56, 58 and the tape 46 into four loops 60, 62, 64, 66. The latter two sets of loops are transversely registered, and in the preferred form of my invention, the loops in each set have a center spacing substantially equal to the center spacing of the first described set of loops 24, 26, 28, 30.

Finally, in accordance with my invention, the diaper is provided with at least two elongated flexible elements such as tapes 68, 70, each of which in use is tied intermediate its ends by an overhand knot 72 to a different one of the series of loops 24, 26, 28, 30. Thus the two tapes are detachably secured to what will, for convenience, hereinafter be referred to as the loops of the center series.

By way of illustration, the attachment of the diaper to a large infant now will be described. The panel 12 is laid on a flat surface such as a bed, with the outer ply 14 lowermost. The baby is placed in position on the diaper with the upper portion 20 extending between the infant's legs. This portion then is drawn up through the crotch and placed on the baby's abdomen. The diaper is arranged so that its upper and lower edges 34, 50 thereupon are approximately in registration. If the tapes 68, 70 have not been previously tied to the proper loops of the center series, said tapes at this time are secured to the upper two loops 24, 26, the overhand knots 72 being located substantially at the center of each tape. The sides of the rear portion 22 are brought up to overlie the side edges of the front portion 20 and the two ends of the tape 68 are threaded through the top

loops 58, 66 of the loops of the side series, brought back toward the center of the upper portion 20 and are tied together, as by a bow 74. The same procedure is repeated for the other tape 70 except that it is threaded through the next loops 56, 64 of the loops of the side series.

If the infant is somewhat smaller, the edges 34, 50 of the front and rear portions may be folded inwardly so as to render the second loops 26, 56, 64 of the central and side series the outermost loops. A diaper so arranged can be placed on or secured to a baby in the same manner as that already described in detail, except that the tapes 68, 70 now are centrally tied to the loops 26, 28 of the center series, and are threaded through the loops 54, 56, 62, 64 of the side series.

Still a further reduction in size of the diaper can be effected by folding down the upper and lower edges a greater degree to make the third loops 28, 54 and 62 the outermost ones. Intermediate sizes may be obtained by folding only one or the other of the front or rear portions or by folding unequally. It may be mentioned that the so-called "front" portion can be placed at the rear of an infant, this term having been employed only to facilitate description.

It thus will be seen that I have provided a diaper which achieves the several objects of my invention and is well adapted to meet the conditions of practical use.

As various possible embodiments might be made of the above invention, and as various changes might be made in the embodiment above set forth, it is to be understood that all matter herein described or shown in the accompanying drawings is to be interpreted as illustrative and not in a limiting sense.

Having thus described my invention, I claim as new and desire to secure by Letters Patent:

40 A diaper comprising an oblong bibulous panel having a crotch portion, at least two tapes, a first portion of said panel to one side of said crotch portion having a linearly arranged series of several spaced elements between the side edges of said first portion to which the tapes are adapted to be tied intermediate their ends, the number of said elements exceeding the number of said tapes, said tapes being tied to adjacent elements, and two linearly arranged series of several spaced elements, one adjacent each side of the panel, said two series of elements being disposed on the portion of the panel to the other side of said crotch portion, said elements being constructed to threadedly pass a tape whereby the ends of the tapes may be threaded through elements of said two series and then tied to one another.

ALEXANDER H. SONNENBERG.
